US0D1013719S

(12) **United States Design Patent** (10) Patent No.: **US D1,013,719 S**
(45) Date of Patent: ** Feb. 6, 2024

(54) **DISPLAY SCREEN OR PORTION THEREOF
WITH GRAPHICAL USER INTERFACE**

- (71) Applicant: **Apple Inc.**, Cupertino, CA (US)
(72) Inventors: **Richard Dellinger**, San Jose, CA (US);
Stephen O. Lemay, Palo Alto, CA (US); **Brandon Walkin**, San Francisco, CA (US)
(73) Assignee: **Apple Inc.**, Cupertino, CA (US)
(**) Term: **15 Years**
(21) Appl. No.: **29/891,316**
(22) Filed: **May 4, 2023**

Related U.S. Application Data

- (63) Continuation of application No. 29/810,322, filed on Oct. 4, 2021, now Pat. No. Des. 989,099, which is a continuation of application No. 29/728,926, filed on Mar. 23, 2020, now Pat. No. Des. 932,502, which is a continuation of application No. 29/664,283, filed on Sep. 24, 2018, now Pat. No. Des. 879,117, which is a continuation of application No. 29/606,391, filed on Jun. 4, 2017, now Pat. No. Des. 829,223.

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
